PUMPING DEVICES

Bruno Tavola, Cellini, Milan, Italy

Application January 16, 1952, Serial No. 266,707

Claims priority, application Italy February 5, 1951

15 Claims. (Cl. 103—37)

The present invention relates to a new and improved pumping device, and more particularly it relates to a new and improved pumping device of the type operating according to the so-called "alternative cycle" and having at least one pressure chamber of cyclically variable cubic capacity varied by a movable member which deforms a resilient portion of the walls of said pressure chamber.

The main object of my present invention is to provide a new and improved pumping device which is not subject to the disadvantages of pumping devices of conventional construction, and in particular it is the object of the present invention to provide a new and improved pumping mechanism in which the pressure chamber forming parts are not in frictional relationship with each to others and in which an annular resilient member, and two rigid members form a pump pressure chamber.

Another object of this my present invention is to provide, in a new and improved pumping device designed for variable output, a special and useful inlet valve device operated by the reciprocating motion of one of the rigid members, and provided with controlling means by which the timing of the action of said inlet valve device may be readily varied at will in respect to the phases of the cyclical contraction and expansion of the pressure chamber. An improved pumping device of the above character may be advantageously used in many practical applications, as liquid fuel injection pump for diesel engines, for example.

A further object of my invention is to provide, in a pumping device having one or more of the above new and useful characteristics, special bearing means for supporting and guiding in a fixed path the reciprocated member or members in relation to the pump housing, without the use of frictional connections between fixed and movable parts.

A still further object of this my present invention is to provide a new and useful pumping device of the above character in which the fluid to be pumped is fed into the pressure chamber or chambers in a new and useful manner, through leak-proof feeding chambers and passages.

A still other object of this my invention is to improve in general the construction of pumping devices having one or more of above useful characteristics, in view of making the manufacture and the assembling of same easy and inexpensive.

Other objects will be in part obvious and in part pointed out hereinafter.

With these objects in view, the present invention mainly consists in a pumping device, which comprises, a pair of spaced plate members, the plate members having oppositely arranged plate faces, at least one of the plate members being reciprocable for reducing and increasing, respectively, the distance between the plate faces, a resilient annular member having two spaced annular sealing end faces and being located between the plate members with the annular sealing end faces abutting against the plate faces of the plate members, inlet and outlet valve

means mounted on the plate members for supplying and discharging a fluid into the interior of the annular member, the inlet valve means being connected to the one plate member for movement therewith, means for reciprocating at least the one plate member whereby the resilient annular member is alternately resiliently compressed, and permitted to resiliently expand while the plate faces and the sealing faces are in permanent sealing abutment, and stationary actuating means engaging the inlet valve means during reciprocating movement of the one plate member for operating the inlet valve means.

One form of construction designed to carry out the invention and which has been found to operate very satisfactorily as a liquid fuel injection pump for small sized and fast running internal combustion engines of the diesel type is shown in the accompanying drawings, by way of example, and it will be hereinafter described in detail, together with other features of the invention.

In the drawings:

Figure 1 is a vertical central sectional view of an embodiment of the fuel pump, partly in section on line 1—1 of Figure 4.

Figures 2 and 3 are sectional views on an enlarged scale, of the pressure chamber, the movable parts being shown in different phases of their cyclical operative motion.

Figure 4 is a view, partly in elevation and partly in section on line 4—4 of Figure 1.

Figure 5 is an exploded view, partly in elevation and partly in section, of the combination of operative parts of the embodiment shown in Fig. 4.

Figure 6 is a cross-sectional view on line 6—6 of Figure 4.

Throughout the figures, like numerals refer to like parts, and numeral 40 in general indicates the pressure chamber. In the following detailed description of my invention, the assembly of the pump, the various parts thereof and the movements of the movable ones thereof will be indicated by using the words "upper," "lower" and respectively "upward" and "downward" with respect to the positions of same in the several figures of the accompanying drawings, it being obvious that the above expressions are not limiting the field and range of the invention and in particular of the appended claims, and that in actual construction and operation any pumping device constructed according to this my invention might be designed and arranged to work in different spatial positions.

The arrangement and cooperation of members, together with other new and useful features forming part of this invention will be apparent from the above described figures of the accompanying drawings, wherein a preferred form of embodiment is shown in which the pump according to the invention comprises a substantially cup-shaped pump housing 10 having an inner chamber

13 and a lower opening 38, and an upper cover member 11 secured to said housing 10 by a suitable securing means, by a securing ring 12 for example. In said chamber 13, which is formed by the pump housing 10 and cover member 11, an axially movable member 14 provided with an enlarged head is arranged and supported by any suitable supporting and guiding means, and in particular by means which will be described in detail as this description proceeds.

The down-facing inner surface 16 of said cover member 11 constitutes the upper surface of the pressure chamber 40 and the up-facing surface 15 of the enlarged head of said movable member 14 constitutes the lower surface of same chamber.

Between the outer portions of the face 16 and of the face 15 of the movable member 14, a substantially ring-shaped or annular side wall forming member 17 of resilient material is arranged in constant abutting relation-

ship with faces 15, 16. The portions of members 14 and 11 which are adjacent the ring member 17 may be termed plate members. The ring-shaped member 17 may conveniently be made of natural rubber, synthetic rubber, resilient plastics and so on, the type and character of the material being obviously a matter of choice, provided that its own characteristics of resiliency and of resistance to chemical and physical actions of the fluid to be pumped meet the specific requirements of operation. Other resilient materials which the most advanced chemistry may or will produce might be advantageously used in the construction of said member 17.

At this point, it will be apparent to those skilled in the art that I provided, in a pumping device operating according to the alternative cycle, a pressure chamber the cubic capacity of which may be alternately increased and reduced, by increasing and reducing, respectively, the spacing of plate faces 15 and 16 of the rigid members 11 and 14. The walls of the pressure chamber are formed by a combination of resilient and rigid members. In fact, the upper and lower annular sealing faces of the annular resilient member 17 made of resilient material are permanently abutting the outer portions of the faces 15, 16 of cover member 11 and of movable member 14, respectively, while no relative motion is imparted to ring member 17 with respect to the cover member 11 and the movable member 14.

It will be readily understood that an absolute sealing of said pressure chamber may easily be obtained in view of the fact that a complete seal may be easily obtained between the contacting surface portions of the resilient ring member 17 and the faces 16 and 15 of cover member and of movable member, respectively. The permanent sealing abutment may be attained simply by suitably dimensioning member 17 so that its axial thickness in normal condition would be larger than the largest spacing between faces 16 and 15 which is obtained during the regular operations of the device. Means may be provided too for assuring the sealing engagement such as a suitable adhesive.

Further, from the above and from a consideration of Figures 2 and 3 it will be understood that I provided a new and useful construction of a pressure chamber the cubic capacity of which may be reduced at a greater extent than corresponding to the "bore to stroke" ratio owing to the fact that the axial compression of said resilient ring 17 produces an inwardly directed bulking of the inner cylindrical surface thereof.

It will still further be apparent that the absolute leak-proofness of pressure chambers of pumping devices according to this my invention permits the design of pumps whose stroke may be smaller than the diameter of the pressure chambers; for example, a form of embodiment of my invention, intended to operate as an injection pump for small and fast running engines, has been found to operate very satisfactorily by imparting to the reciprocated member 14 a stroke from $\frac{1}{100}$ to $\frac{3}{100}$ of an inch. The use of such small stroke values obviously offers very remarkable advantages, a very low linear speed value even though the pump is driven at very high speed, small wear of movable parts, reduction of the driving power, fast action of the pumping phase, exact timing, and so on.

In the illustrated embodiment the pumping device has a substantially conventional outlet check valve 18 including a ball 19 urged by a spring 20 against a suitable seat.

In the illustrated embodiment the inlet valve means comprises a frusto conical seat 21 drilled in the center of plate face 15 of the movable member 14, and cooperating with a poppet valve 22, made integral with a stem 23 which is slidably supported for axial movement in movable member 14, a coil spring 27 being provided for urging said poppet valve 22 against its seat 21. A stop member 24 connected to the fixed structure of the pumping device is provided for limiting the downward motion of poppet valve 21 in respect to said fixed structure, the stop mem-

ber being so positioned that it stops the downward motion of the inlet valve means 22-23, which moves together with said movable member 14 during the down-stroke thereof, before that said movable member reaches to its lowermost position. Consequently the stop member constitutes an actuating means for the inlet valve. During the down stroke of movable member 14 the seat 21 of said poppet valve 22 detaches itself from said valve 22, opening the same. Likewise, during the up-stroke of said movable member, at a certain position the seat 21 in movable member 14 reaches its contacting position with said valve 22, closing the same. It is to be pointed out that in my described new inlet valve device the operation of the valve is carried out by moving the "seat" in respect to the "valve."

From the above it will be apparent to those skilled in the art that the actual operative cubic capacity of the pumping device does not depend on the whole stroke but on the stroke portion between the lowermost position and the position in which the inlet valve closes. Having this operative feature in mind, it will be readily understood that by providing suitable means for timing the actuation of the inlet valve the actual operative cubic capacity of the pumping device might be varied at will.

For this purpose a cam-shaped portion 24 in a transverse shaft 25 is provided as stop member for actuating the inlet valve 22, the shaft 25 pressing diametrically through both said movable member 14 and said pump housing 10, and rotatably supported by the latter, elongated transverse passages 39 being provided in said movable member for allowing free passage of said shaft while the movable member is reciprocated, so that the lower end of said stem 23 of valve 22 abuts on cam portion 24 as movable member 14 approaches to its lowermost position. One end of said shaft 25 extends outside said pump housing 10 and it is connected to any suitable control means such as arm-lever 26. By rotating shaft 25, the lowermost position of valve 22, i. e. the contacting position along the stroke motions of the movable member 14, may be varied at will within the desired range of operation. The radii of said cam-shaped portion 24 might be easily designed to shift the actual lowermost position of said valve up to or above the uppermost position which it would reach in contacting relationship with its seat, if a control range extending up to zero out-put is desired.

In a pumping device according to this my invention, any suitable driving means may be provided for reciprocating the movable member 14. In the preferred form of embodiment shown the movable member 14 is provided with a threadedly connected lower portion 28 extending out of pump housing 10 through said bottom opening 38, said lower portion being operated by a cam 29. Of course, other drive means might be substituted according to the different specific requirements of operation: for pumping devices in which a brief and exactly timed pumping phase is not required, a conventional crank and connecting rod device, an eccentric driving wheel, or a slot-and-crank device may be provided.

In the case that a cam or an operatively equivalent device is provided for reciprocating the movable member, the backward stroke of said member might be obtained by using the same resilient substantially ring-shaped member 17, owing to its resiliency. The use of a more efficient spring means is however deemed preferable, in particular in case of embodiment of this invention designed to run at higher speed. As shown in the accompanying drawing, preferably I provide a coil spring 33 for co-operation with cam 29. The coil spring is arranged around said movable member 14 and its ends abut on an in-turned flange forming ring member 36, fixedly connected to the pump housing (in particular, tightly closed between a step 41 provided in said housing 10 and the lower edge 42 of cover member 11, see Figure 5) and on an out-turned flange forming ring member 37 fixedly connected to said movable member 14 (in particular, tightly closed between

a step 43 provided in said movable member 14 and the upper edge 44 of the lower portion 28 of the movable assembly, see Figure 5). It will be apparent that said spring 33 urges the movable assembly comprising members 14 and 28 in downward direction.

Further, any suitable guiding means may be used for guiding the movable member along its fixed path in axial relationship with the pressure chamber, slide bars or other sliding devices, for example, and a suitable means may be provided too in bottom opening 38 for sealing the inner chamber 13, if desired. The fluid to be pumped is fed under a certain pressure into said inner chamber 13 through an inlet passage 31, from any suitable source of pressurized fluid (not shown).

For carrying out said simple system for feeding the pressure chamber with pressurized fluid fed into said inner chamber 13 of the pump housing, I provide the movable member 14 with passages 32 through which said inner chamber 13 communicates with the valve opening encircled by seat 21 of poppet valve, through which said inner chamber 13 communicates with the pressure chamber 40, provided that seat 21 is detached from poppet valve 22.

A second substantially ring-shaped member made of resilient material is arranged in said bottom opening 38 of pump housing and fixedly connected at its outer edge to the wall of said opening and at its inner edge to the lower portion of the movable assembly which is axially reciprocated through said bottom opening.

In the form of embodiment shown in the accompanying drawings, the sealing of the annular space comprised between the inner surface of opening 38 and the outer surface of lower portion 28 of the movable elements is sealed by a flat ring-shaped member 30 of resilient material, the outer edge of which is inserted into an annular groove 45 provided in said inner surface of opening 38 and whose inner edge of which is inserted into an annular groove 46 provided in said lower portion 28 of the movable elements (Figure 5), the portion of said ring-shaped member 30 between said outer and inner inserted portions being wide enough to allow the bending of said resilient member as necessary in view of the reciprocating motion of said movable assembly in respect to said pump housing. Consequently chamber 13 is reliably sealed and the movable elements centered in opening 38. The resilient ring member 17 acts as an efficient centering means of same movable elements, in respect to the upper portion thereof. The said second resilient ring-shaped member 30 may be made of natural rubber, synthetic rubber, resilient plastic, and so on, and also it might be made by a resilient thin metallic sheet, which may be corrugated.

The operation of a pumping device constructed as above described and shown in the accompanying drawings will be apparent from the following description, referring in particular to Figures 2 and 3.

Provided that cam 29 is properly connected in the necessary timed relationship with a rotating part of the internal combustion engine the injector of which is to be fed by the pump, and provided that the inlet passage 31 is connected to a suitable supply means of pressurized liquid fuel, the inner chamber 13 will be full of pressurized liquid. Supposing now the movable member 14 to be at its lowermost position (Figures 1 and 4), the poppet valve 22 at its lowermost position permitted by the abutment of the lower end of its stem 23 on cam portion 24 of shaft 25, the valve member 22 is detached from its seat 21, thus allowing free admission of fuel from chamber 13 and through passages 32 into pressure chamber 40, which is filled while the outlet ball valve 19 is kept in closed position by spring 20. By operation of cam 29, the movable rigid member 14 then starts on its up-stroke motion, in direction A, and the spacing of movable face 15 from face 16 will progressively decrease, while the side wall formed by inner surfaces of the substantially annular resilient member 17 will be subject to progressive inward bulging. The volume of pressure chamber 40 is progressively reduced but, owing to the

fact that until seat 21 engages valve 22 pressure chamber 40 is not separated from feeding chamber 13, the excess fuel due to the diminishing capacity of pressure chamber 40 is back-fed into said feeding chamber 13 in direction B (Figure 2).

As the upward motion of movable member 14 proceeds, at a certain point of said motion seat 21 engages poppet valve 22, effecting the separation of pressure chamber 40 from feeding chamber 13. At this point the actual operative pumping phase starts, and any subsequent reduction of cubic capacity of said chamber 40 causes the discharge of the liquid fuel in direction C through outlet valve 18, the ball 19 of which is forced open by the pressure until said movable member 14 reaches its uppermost position.

15 It will be apparent from above that the amount of liquid delivered at any cycle of operation of the pump may be varied by rotating cam portion 24, i. e. by varying the position of said contacting position of seat 21 with valve 22 in respect to the amplitude of up-stroke of movable member 14. The later the contact occurs during the up-stroke motion the smaller is the cyclical out-put.

20 In the form of embodiment shown, the pumping device according to this my invention is designed chiefly for injecting fuel in a combustion chamber of a single cylinder small engine; however, it will be apparent the features above described or their equivalents may advantageously be applied to the construction of pumps for multi-cylinder engines, and for any other field of application in which a pumping device is necessary. Further, 25 a pumping device of the character described or its equivalent may usefully be provided with auxiliary devices and features, by applying current knowledge in the art; for example, the pump shown in the accompanying drawings is provided with a discharge passage 34 normally 30 kept close by a needle valve 35 for a convenient time to time vent air from pressure chamber 40.

35 It is to be further understood that the device above described may be further improved both in its structure and in its operation, by combining the above disclosed 40 features with other devices, features and methods that those skilled in the art may readily apply and use by applying current knowledge. Consequently, while I have herein described a preferred single embodiment of my invention, the invention is not intended to be limited thereto, and other embodiments and modifications incorporating one or more of any advantageous features and of any novel functions of the form herein disclosed and embraced by the appended claims will be apparent to those skilled in the art.

Having thus described the invention, what I claim as 50 new and desire to have protected by Letters Patent is:

1. In a pumping device a first rigid member, having a first face, a second rigid member in variably spaced relationship with said first rigid member and having a second face opposite said first face, a substantially ring-shaped member, made of resilient material, in abutting relationship with both said faces and having a cylindrical inner surface defining with said faces a pressure chamber, driving means for reciprocating one of said rigid members in respect to other of said rigid members as 55 to vary the spaced relationship thereof within the limits allowed by the expansion and compression of said resilient substantially ring-shaped member abutting thereon, a valve seat forming inlet opening being formed in said face of said one of said rigid members, a valve movably supported by said one of said rigid members so as to 60 cooperate with said seat for closing said inlet opening, means for detaching said valve from said seat in timed relationship with the cycle of operation of the device, said means comprising a stop member connected to the 65 other of said rigid members and arranged to actuate said valve to detach itself from said seat as said one said rigid member approaches to its most spaced position from the other said rigid member, and outlet check valve means 70 mounted on the other of said rigid members and communicating with said pressure chamber.

75

2. In a pumping device a first rigid member, having a first face, a second rigid member in variably spaced relationship with said first rigid member and having a second face opposite said first face, a substantially ring-shaped member, made of resilient material, in abutting relationship with both said faces and having a cylindrical inner surface defining with said faces a pressure chamber, driving means for reciprocating one of said rigid members in respect to other of said rigid members as to vary the spaced relationship thereof within the limits allowed by the expansion and compression of said resilient substantially ring-shaped member abutting thereon, a valve seat forming inlet opening being formed in said face of said one of said rigid members, a valve movably supported by said one of said rigid members so as to cooperate with said seat for closing said inlet opening, and means for detaching said valve from said seat in timed relationship with the cycle of operation of the device, said means comprising a stop member movably connected to the other of said rigid members and arranged to actuate said valve to detach itself from said seat as said one said rigid member approaches to its most spaced position from the other said rigid member, means for varying the position of said stop member in respect to the different relative positions of said rigid members in variably spaced relationship, and outlet check valve means mounted on the other of said rigid members and communicating with said pressure chamber.

3. A pumping device particularly designed as liquid fuel injection pump, comprising, in combination, a pump housing having an inner chamber provided with an inner top surface, with a lower opening and with an inlet opening for connection with a pressurized fuel supply means, a movable member movably supported into said chamber in axial relationship with said inner top surface and downwardly extended through said lower opening and having an upper surface in opposed and spaced relation to said inner top surface, said movable member being formed with a valve seat forming opening in said upper surface, a valve movably supported in said movably supported member and cooperating with said valve seat for closing said opening, said movable member being formed with passage means connecting said opening to the lower portion of said inner chamber, driving means for reciprocating said movably supported member in respect to said pump housing, a first substantially ring-shaped member made of resilient material and arranged between said inner top surface and said upper surface and in constant abutting relationship with the outer portions thereof, a second substantially ring-shaped member of resilient material having its outer edge fixedly connected to inner edge of lower opening and its inner edge fixedly connected to said movably supported member for movably supporting the same in cooperation with said first substantially ring-shaped member and for sealing said inner chamber, and a stop member connected to said pump housing and positioned to stop the downward motion of said valve as said movably supported member approaches its lowermost position, for causing said valve seat to be displaced from said valve.

4. A pumping device particularly designed as liquid fuel injection pump, comprising, in combination, a pump housing having an inner chamber provided with an inner top surface, with a lower opening and with an inlet opening for connection with a pressurized fuel supply means, a movable member movably supported into said chamber in axial relationship with said inner top surface and downwardly extended through said lower opening and having an upper surface in opposed and spaced relation to said inner top surface, said movable member being formed with a valve seat forming opening in said upper surface, a valve movably supported in said movably supported member and cooperating with said valve seat for closing said opening, said movable member being formed with passage means connecting said opening to the lower portion of said inner chamber, driving means for reciprocating said movable member in respect to said pump housing, a first substantially ring-shaped member made of resilient material and arranged between said inner top surface and said upper surface and in constant abutting relationship with the outer portions thereof, a second substantially ring-shaped member of resilient material having its outer edge fixedly connected to inner edge of lower opening and its inner edge fixedly connected to said movable member for movably supporting the same in cooperation with said first substantially ring-shaped member and for sealing said inner chamber, and a stop member connected to said pump housing and positioned to stop the downward motion of said valve as said movable member approaches its lowermost position, for causing said valve seat to be displaced from said valve.

5. In the lower portion of said inner chamber, driving means for reciprocating said movably supported member in respect to said pump housing, a first substantially ring-shaped member made of resilient material and arranged between said inner top surface and said upper surface and in constant abutting relationship with the outer portions thereof, a second substantially ring-shaped member of resilient material having its outer edge fixedly connected to inner edge of lower opening and its inner edge fixedly connected to said movably supported member for movably supporting the same in cooperation with said first substantially ring-shaped member and for sealing said inner chamber, a stop member turnably mounted in said pump housing and having a turnable cam-shaped portion positioned to contact said valve during the downward motion thereof as said movably supported member approaches its lowermost position, for causing said valve seat to be displaced from said valve, and control means for turning said stop member and said cam-shaped portion.

6. A pumping device particularly designed as liquid fuel injection pump, comprising, in combination, a pump housing having an inner chamber provided with an inner top surface, with a lower opening and with an inlet opening for connection with a pressurized fuel supply means, a movable member movably supported into said chamber in axial relationship with said inner top surface and downwardly extended through said lower opening and having an upper surface in opposed and spaced relation to said inner top surface, said movable member being formed with a valve seat forming opening in said upper surface and with a transverse passage, a poppet valve having a stem, slidably supported in said movably supported member and cooperating with said valve seat for closing said opening, said movable member being formed with passage means connecting said opening to the lower portion of said inner chamber, cam-type driving means for imparting an up-stroke motion and spring means for imparting a down-stroke motion to said movably supported member, a first substantially ring-shaped member made of resilient material and arranged between said inner top surface and said upper surface and in constant abutting relationship with the outer portions thereof, a second substantially ring-shaped member of resilient material having its outer edge fixedly connected to inner edge of lower opening and its inner edge fixedly connected to said movably supported member for movably supporting the same in cooperation with said first substantially ring-shaped member and for sealing said inner chamber, a shaft rotatively supported by said pump housing and transversely passing through the latter and through said transverse passage in said movably supported member, and having a portion extending outside said housing for manual operation, and a cam-shaped portion positioned under the lower end of said stem and acting as adjustable stop means to stop the downward motion of said valve during downward strokes of said movably supported member as said movably supported member approaches its lowermost position, for causing said valve seat to be displaced from said valve.

60 6. In a pump, in combination, a pair of spaced plate members, said plate members having oppositely arranged plate faces, at least one of said plate members being reciprocable for reducing and increasing, respectively, the distance between said plate faces; a resilient annular member having two spaced annular sealing end faces and being located between said plate members with said annular sealing end faces abutting against said plate faces of said plate members; inlet and outlet valve means mounted on said plate members for supplying and discharging a fluid into the interior of said annular member, said inlet valve means being connected to said one plate member for movement therewith; means for reciprocating at least said one plate member whereby said resilient annular member is alternately resiliently compressed, and permitted to resiliently expand while said plate faces and said sealing

faces are in permanent sealing abutment; and stationary actuating means engaging said inlet valve means during reciprocating movement of said one plate member for operating said inlet valve means.

7. In a pump, in combination, a pair of spaced plate members, said plate members having oppositely arranged plate faces, at least one of said plate members being reciprocable for reducing and increasing, respectively, the distance between said plate faces; a resilient annular member having two spaced annular sealing end faces and being located between said plate members with said annular sealing end faces abutting against said plate faces of said plate members; inlet and outlet valve means mounted on said plate members for supplying and discharging a fluid into the interior of said annular member, said inlet valve means being connected to said one plate member for movement therewith; means for reciprocating at least said one plate member whereby said resilient annular member is alternately resiliently compressed, and permitted to resiliently expand while said plate faces and said sealing faces are in permanent sealing abutment; and stationary actuating means engaging said inlet valve means during reciprocating movement of said one plate member for operating said inlet valve means, said actuating means being adjustable for determining the timing of operation of said inlet valve means with respect to the reciprocating movement of said one plate member.

8. In a pump, in combination, a pair of spaced plate members, said plate members having oppositely arranged parallel plate faces, at least one of said plate members being reciprocable for reducing and increasing, respectively, the distance between said plate faces; a resilient annular member having two spaced parallel annular sealing end faces and being located between said plate members with said annular sealing end faces abutting against said plate faces of said plate members; inlet and outlet valve means mounted on said plate members for supplying and discharging a fluid into the interior of said annular member, said inlet valve means being connected to said one plate member for movement therewith; means for reciprocating at least said one plate member whereby said resilient annular member is alternately resiliently compressed, and permitted to resiliently expand while said plate faces and said sealing faces are in permanent sealing abutment; and stationary actuating means including a rotary cam means engaging said inlet valve means during reciprocating movement of said one plate member for operating said inlet valve means, the timing of the engagement of said inlet valve means by said cam means being adjustable by rotation of said cam means.

9. An arrangement as claimed in claim 8 and including manually operated means for rotating said cam means.

10. An arrangement as claimed in claim 8 wherein said outlet valve means includes resilient means for automatic closure of said outlet valve means, said outlet valve means being adapted to be opened against the action of said resilient means by the fluid pressure produced by the reciprocation of said one plate member.

11. In a pump, in combination, a pair of spaced plate members, said plate members having oppositely arranged parallel plate faces, at least one of said plate members being reciprocable for reducing and increasing, respectively, the distance between said plate faces; a resilient annular member having two spaced parallel annular sealing end faces and being located between said plate members with said annular sealing end faces abutting against said plate faces of said plate members; inlet and outlet valve means mounted on said plate members for supplying and discharging a fluid into the interior of said annular member, said inlet valve means being connected to said one plate member for movement therewith; spring means urging said one plate member away from said other plate member; and a rotary cam member engaging said one plate member for moving said one plate member

toward the other of said plate members against the action of said spring means whereby said one plate member is reciprocated and said resilient annular member is alternately resiliently compressed, and permitted to resiliently expand while said plate faces and said sealing faces are in permanent sealing abutment; and stationary actuating means engaging said inlet valve means during reciprocating movement of said one plate member for operating said inlet valve means.

12. A pump comprising, in combination, a casing having an inlet; a fixed plate member secured to said casing, and defining with the same a chamber communicating with the outside through said inlet in said casing; a movable plate member reciprocably mounted in said chamber, said plate members having oppositely arranged parallel faces, the distance between said faces being reduced and increased, respectively, during reciprocation of said movable plate member, said movable plate member being formed with conduit means connecting said chamber in said casing with a central portion of said face of said movable plate member; inlet valve means located in said central portion of said face of said movable plate member communicating with said conduit means; an annular spring loaded check valve means in a central portion of said fixed plate member; an annular resilient member having two spaced parallel annular sealing faces and being located between said plate members with said annular sealing faces abutting against said faces of said plate members and surrounding said central portions; and means for reciprocating said movable plate member whereby said resilient annular member is alternately resiliently compressed and permitted to resiliently expand during reciprocation of said movable member with said faces in permanent sealing abutment.

13. A pump comprising, in combination, a casing having an inlet; a fixed plate member secured to said casing, and defining with the same a chamber communicating with the outside through said inlet in said casing; a movable plate member reciprocably mounted in said chamber, said plate members having oppositely arranged parallel faces, the distance between said faces being reduced and increased, respectively, during reciprocation of said movable plate member, said movable plate member being formed with conduit means connecting said chamber in said casing with a central portion of said face of said movable plate member; inlet valve means located in said central portion of said face of said movable plate member communicating with said conduit means; an annular spring loaded check valve means in a central portion of said fixed plate member; an annular resilient member having two spaced parallel annular sealing faces and being located between said plate members with said annular sealing faces abutting against said faces of said plate members and surrounding said central portions; means for reciprocating said movable plate member whereby said resilient annular member is alternately resiliently compressed and permitted to resiliently expand during reciprocation of said movable member with said faces in permanent sealing abutment; and actuating means mounted in said casing and connected to said fixed plate member and engaging said inlet valve means during reciprocating movement of said movable plate member for operating said inlet valve means.

14. A pump comprising, in combination, a casing having an inlet; a fixed plate member secured to said casing, and defining with the same a chamber communicating with the outside through said inlet in said casing; a movable plate member reciprocably mounted in said chamber, said plate members having oppositely arranged parallel faces, the distance between said faces being reduced and increased, respectively, during reciprocation of said movable plate member, said movable plate member being formed with conduit means connecting said chamber in said casing with a central portion of said face of said movable plate member; inlet valve means located in said

central portion of said face of said movable plate member communicating with said conduit means; an annular spring loaded check valve means in a central portion of said fixed plate member; an annular resilient member having two spaced parallel annular sealing faces and being located between said plate members with said annular sealing faces abutting against said faces of said plate members and surrounding said central portions; means for reciprocating said movable plate member whereby said resilient annular member is alternately resiliently compressed and permitted to resiliently expand during reciprocation of said movable member with said faces in permanent sealing abutment; and a manually operated rotary actuating cam means mounted in said casing turnable about an axis transverse to the direction of reciprocation of said movable plate member, said rotary cam means engaging said inlet valve means during reciprocation of said movable plate member for operating said inlet valve means, the timing of the operation of said inlet valve means being determined by the position of said rotary cam means.

15. In a pump, in combination, a casing having an inlet; a fixed plate member secured to said casing and defining with the same a chamber communicating with the outside through said inlet in said casing; a movable plate member located in said chamber, said plate members having oppositely arranged parallel plate faces, said movable plate member and said casing being formed with op-

positely arranged annular grooves; a resilient supporting ring means located between said movable plate member and said casing and projecting into said annular grooves of said members for movably supporting said movable plate member; a resilient annular member located between said plate members and having annular sealing faces abutting against said plate members; inlet and outlet valve means mounted on said plate members for supplying and discharging a fluid into the interior of said annular member, said inlet valve means being connected to said one plate member for movement therewith; means for reciprocating said movable plate member whereby said annular member is alternately resiliently compressed and permitted to expand resiliently; and stationary actuating means engaging said inlet valve means during reciprocating movement of said movable plate member for operating said inlet valve means.
